UNITED STATES PATENT OFFICE.

GENNARO DE PAMPHILIS, OF NEW YORK, N. Y.

PRINTING-PRESS GAUGE.

Application filed November 14, 1927. Serial No. 233,186.

This invention relates to gauges as used in combination with tympan or top sheets on printing press platens to guide the blanks to be printed and cause them to register 5 correctly with the type.

It is one of the objects of this invention to provide a particularly effective device capable of being speedily and positively clamped to the tympan sheet when in ad- 10 justed position.

A further feature is in the provision of means whereby a single guide finger may be held firmly at either side of the gauge or two guides used at the same time.

Another purpose is to produce a gauge having a slitting blade by which an incision 15 in the tympan sheet may be made without the use of accessories or auxiliary implements.

A further object is to provide a cam 20 clamping device readily operated and which is rigid and secure in its operation.

These and other advantages such as simplicity, compactness and neatness of appearance, are accomplished by the novel and practical construction and combination of parts hereinafter described and illustrated in the accompanying drawing, forming an essential part of this disclosure, and in which:—

Figure 1 is a perspective view of an embodiment of the invention illustrating its application.

Figure 2 is an enlarged longitudinal sectional view of the device as in an applied or 35 operative position.

Figure 3 is a similar sectional view but showing the upper element in a raised position.

Figure 4 is a bottom plan view of the 40 gauge showing the cam locking means.

Referring in greater detail to the drawings, the numeral 10 designates a portion of the platen of a conventional printing press on which is disposed a tympan sheet 45 11, having a slit 12.

The gauge consists of two main parts, respectively upper and lower, the latter being an oblong rectangular metal plate 14 beveled at its front end to produce a sharp blade 50 15 having rounded cutting corners 16 by which the slit 12 may be easily made.

Adjacent the knife blade edge are a plurality of sharp upstanding prongs 17 and substantially at the center of the plate is 55 a circular concave recess 18 formed by indenting the material from the under side

and a longitudinal slot 19 extends through the recessed metal.

The wall of the recess, at the sides of the slot 19, are shaped to produce opposed wedge 60 shaped cam surfaces 20 for a purpose further on described.

At the opposite rear end of the plate the metal is sheared and curled upward to provide spaced hinge elements 21 through which 65 is passed a pin 22, the same connecting a reversely curled hinge element 23 extending from the rear element of an open rectangular box-like metal frame having a cover plate 24 and marginal, down-reaching flanges 25 70 of uniform length on all four sides.

The rear flange, as noted, is extended to form the hinge member 23 and the opposite, front flange is adapted to make contact with the base plate 14, closely adjacent the rear 75 of the prongs 17.

At the center of the frame plate 24 the metal is pierced and down-turned to form a tubular bearing 26 receptive of a revoluble and slidable stem 27 provided at its outer 80 end with a fixed button head 28, having a sharply corrugated outer face on which is a distinct line 29.

Fixed on the inner end of the stem is a cross bar 30 adapted to be pressed through 85 the tympan sheet 11, pass through the base plate slot 19 and be turned at an angle to engage the cam faces 20, the upper ends of the bar being shaped to produce corresponding cam faces 31.

Formed through the front and rear end flanges 24 of the frame, adjacent the side flanges and directly below the plate 24, are elongated rectangular openings 32 adapted to receive guide strip fingers 33, which may 95 be curved upwardly at their forward projecting ends 34, and bent to frictionally engage the under side of the plate 24, the material of these strips being amenable to such distortion so as to be retained in any 100 desired adjustment.

It is to be noted that two of these strips may be used at the same time or a single strip in either the right or left hand openings as may be preferred.

In operation, an incision is made in the tympan sheet by the blade 15, the lower plate 14 inserted therethrough and thereafter the upper element turned down upon the hinge.

By noting the position of the line 29 the bar 30 is brought into registration with the

slot 19, whereupon the bar is forced through the tympan sheet by pressure applied to the button head 28, which is thereafter turned, locking the gauge fixedly to the tympan sheet.

Due to the slot 11' made through the tympan sheet the gauge may be adjusted endwise and obviously the fingers 33 may be moved to suit requirements.

10 From the foregoing it will be seen that a simple device for this purpose has been disclosed in the preferred form of its embodiment, but it is not desired to restrict the details to the exact instruction shown, it being 15 obvious that changes, not involving the exercise of invention, may be made without conflicting with the scope of the appended claims.

Having thus described my invention, what 20 I claim as new and desire to secure by Letters Patent, is:—

1. A gauge for use in combination with a tympan sheet comprising a base plate to pass through a slit in said sheet, said plate having 25 an apertured recess, a frame hinged to said plate to rest over said sheet, means in said frame to adjustably carry one or more guide strips, a manually operable head rotatably mounted in said frame, and cam means 30 actuated by said head to engage in the base recess and clamp said frame to the base.

2. A gauge for use in combination with a tympan sheet comprising a base plate having 35 means for slitting the sheet to enter thereunder, a frame having a marginal flange hinged to said base plate, said plate having a central cavity provided with opposed cam surfaces and containing a longi-

tudinal slot, a cross bar having co-operating cam surfaces to pierce the tympan sheet, pass 40 through the slot and engage the same surfaces in the base plate recess, a handled stem on said cross-bar journaled in said frame, and means adjacent the sides of said frame to receive guide strips. 45

3. A printing press gauge comprising a base plate adapted to pass through a sheet of tympan paper, said plate having a raised circular central recess containing a slot and opposed cams at the sides thereof, a shallow 50 rectangular frame hinged to said plate, a stem revoluble in said frame, a cross bar on said stem having cam surfaces to engage the cams in the base recess, a corrugated head on said stud by which the bar may be forced through the paper to engage or disengage the cams in clamping the paper between said base and frame, and means in said frame to carry one or more gauge strips. 55

4. A printing press gauge comprising a base plate having a raised central portion containing a longitudinal slot, opposed cam faces at the sides of the slot, a cutting edge on one end of said plate, prongs adjacent said edge, a hinge on the opposite edge, a rectangular frame secured by the hinge, means at the marginal sides of said frame to engage longitudinal spring guides, a knurled button having a stem rotatable centrally in said frame, a clamp bar member carried on the inner end of said stem to pass through the slot in said base and engage said cam faces, and means on said button to indicate the position of said bar. 60

In testimony whereof I affix my signature.
GENNARO DE PAMPHILIS.
